OF ALAMEDA, CALIFORNIA.

IMPACT WATER-MOTOR.

1,038,538.

Specification of Letters Patent. Patented Sept. 17, 1912.

Application filed November 16, 1906, Serial No. 343,732. Renewed July 22, 1912. Serial No. 710,977.

To all whom it may concern:

Be it known that I, WILLIAM A. DOBLE, a citizen of the United States, and residing at San Francisco, San Francisco county, State 5 of California, have invented certain new and useful Improvements in Impact Water-Motors, of which the following is a specification.

In those forms of hydraulic apparatus in 10 which the power is derived from a jet or stream of water directed through a nozzle connected with a pipe supplied with water under a very high pressure, the slow reduction of the size of the discharge orifice 15 does not give rise to a much greater degree of pressure, but a sudden reduction in the size of the outflow from said orifice results in a very great increase of pressure which has the suddenness of action and effective 20 result of a blow, and is ordinarily termed "water hammer," and its frequent effect is to burst the pipe. Further, if the reduction in the discharge orifice or retardation of discharge takes place at a uniform rate, 25 the pressure will continuously increase, finally reaching its maximum at the instant the orifice is fully closed, but if the rate of closing gradually diminishes there is no material or sudden increase of pressure and 30 no danger to the apparatus.

The object of my invention is to avoid the results of rapidly closing the valves of such apparatus, especially those in which the jet is employed to operate upon the 35 blades of an impact water wheel, and to this end I provide the apparatus with a supplemental port, with means for insuring its proper opening and closing, so as not only to avoid water hammer, but also to prevent 40 waste of water.

In the accompanying drawing the figure illustrates in elevation sufficient of an impact water motor, partly in section, to enable my improvements to be understood.

45 The valve casing A is of any suitable construction, provided with a discharge nozzle 4, having a port 5, and also with another or supplemental port 6, which is within a branch nozzle 7, and as shown, the nozzle 4 is so arranged that the jet from the main 50 port 5 is projected against the blades 8 of an impact wheel B of suitable construction.

The port 5 is controlled by a valve C, preferably a needle valve of the construction 55 shown in my Letters Patent No. 660,789

but may be otherwise constructed, and the port 6 which as shown is less in area than the port 5 is closed by a valve D which may approximate in form the valve C, but in any event, preferably has a head 9 so arranged upon the stem 10 as to receive water pressure from the casing A or from the main supply, in such a manner that it acts upon the head to tend to close the valve.

With the two valves is combined an operating device, by the movement of which both valves may be mechanically opened and closed, permitting both valves to be closed at the same time and also allowing either to be opened and closed independently of the other.

As shown, a lever 12 is pivoted between its ends to the frame of the apparatus and is connected by a link to the stem 13 of the valve C, and a relay comprising dashpot 75 or cataract device or any other device, which will interpose a yielding medium between the other end of the lever and the valve D, is interposed in the line of connection. Thus, as shown, the rod 14 of the piston 15 80 of the dashpot is connected to the lower end of the lever 12, the said piston sliding in the cylinder 16 which is jointed to the valve stem 10 and is prevented from turning by a guide rod 18, extending from the cylinder 85 through a slot of a bracket 17 on the frame.

Above the cylinder 16 of the dashpot is a casing 19 containing a chamber partially filled with liquid which also fills the cylinder, and between the casing 19 and the cylinder there are three communications or 90 ports 20, 21, 22, the size of the last named being controlled by an adjustable screw valve 23, and the port 21 being provided with a perforated detachable bushing 24 to 95 permit bushings with perforations of different sizes to be substituted for each other to control the speed of operation of the parts.

The piston 15 has ports 26 and a valve 27 closing when the lever 12 is swung in the 100 direction of its arrow, the valve being kept normally to its seat by a spring 28.

Different means may be employed for swinging the operating lever 12. As shown, the upper end is connected by a link to the 105 arm of a pivoted sector 30 carrying a curved rack 31 meshing with a gear 32 upon a shaft 33, which is rotated by the action of governing mechanism J of any suitable character in any suitable manner, the said mecha- 110

nism being as shown actuated from the shaft 34 of the wheel B, or otherwise.

As shown, both ports are closed, and to start the apparatus, it is necessary to turn the shaft 33 by hand in the direction of the arrow, when the valve C will be withdrawn from its port and the jet from the said port will impinge upon the blades of the wheel B and turn the same.

- 10 At every change of load on the water wheel the governor shifts the position of the regulating valve C in the main nozzle and thereby regulates the size of the jet applied to the wheel so as to provide just sufficient water to carry the load output desired. Therefore, if the wheel is operating at a full load, and a certain proportion, say one-quarter of the load, is suddenly thrown off, the governor instantly shifts the controlling needle 20 of the main nozzle one-quarter of its stroke, and thus so regulates the jet as to maintain a constant speed of rotation of the wheel, and the consumption of water by the wheel will be one-quarter less than in operating at the full load, which difference in the amount of water supply is of course preserved in the reservoir for future use.

In opening the main nozzle the upper end of the lever 12 moves back, withdrawing the 30 valve C; the lower end moves forward, pushing forward the piston 26; the pressure on the oil in front of said piston opens the large relief valve 27, and the oil passes through the piston to the rear, and may also 35 flow to a limited extent through the ports 20 and 22, to the rear. Thus the forward movement of the piston is in no way impeded. At the full opening of the main nozzle the piston occupies the position shown in 40 dotted lines.

Assuming that the main nozzle is closing, the lower end of the lever 12 moves back in the direction of its arrow; the piston 26 is carried back, forcing the oil through the 45 ports 22, 21 and 20, the port 21 being open wide enough to allow the oil to flow freely from the cylinder 16 during the first portion of the backward stroke of the piston, so that the movement of the latter will not generally 50 effect that of the valve 9 until the piston covers to port 21. Thus a certain amount of slip or lost motion is permitted between the piston and the cylinder 16 and valve 9 to maintain the said valve stationary during 55 a certain part, say from one-half to three quarters, of the full closing movement of the valve C. When however the piston 26 has closed the port 21, the only outlet for the oil in the rear end of the cylinder 16 is 60 through the restricted port 22, and the oil cannot generally pass rapidly enough to permit the piston to uncover the port 21 so that practically the piston and the cylinder 16 are locked together and will move back together, drawing with them the valve D and

operating the lower port 6. This operation of course will take place if the closing movement of the valve C is at all sudden, or of so rapid a character as to tend to cause an over pressure in the pipes. If the valve C should be closed so slowly that the oil in the cylinder 16 can escape through the port 22 to the opposite end of the cylinder at a speed proportionate to the rate of movement of the piston, then in that case there will be no 70 locking of the piston and cylinder 16 together, and the main valve can be closed to its full extent without opening the compensating valve.

After the compensating valve has been 80 opened under a sudden closure of the valve C there will be a stream of water running to waste from the auxiliary nozzle. The pressure of the water against the valve D however tends to close this valve and the cylinder 16 will be carried with the valve, the piston 26 remaining stationary. This puts the oil in the rear of the cylinder 16 under such pressure that it slowly flows out through the port 22, allowing the cylinder 90 and needle to move forward slowly until the nozzle 7 is finally closed and the waste of water stopped, this closure being effected so slowly that there can be no detrimental rapid increase of pressure in the pipes and 95 passages.

The time at which the relief action of the compensating device begins depends upon the size of the port 21, being determined by experiment in each particular case. It 100 will be seen however that if the closing motion of the main valve is extremely rapid, the compensating valve will be moved back to some extent before the port 21 is fully covered, unless such port is made of such a 105 size as to prevent this result. The adjustment of the screw valve 23 closing the port 22 must of course be made under service conditions, being tested until such a position of the valve is found that when the governor closes the main nozzle at its most rapid rate the compensating valve shall be permitted to move back at a speed that will prevent detrimental pressure.

It will be seen that by the above described 115 means I am enabled to secure an absolute control over the time of opening of the auxiliary or compensating nozzle, that so long as the load fluctuations on the wheel are within a predetermined limit, the compensating device remains inactive, and that therefore the water consumption of the wheel is proportional to the power output. When however the load is suddenly thrown off the wheel, or when load changes occur 120 of a greater magnitude than those for which the devices are set, and of such magnitude as to be sufficient to produce a water ram, or detrimental increase of pressure in the pipe line beyond the permissible amount, 130

the auxiliary or compensating device will result in an immediate opening of the supplemental port. It will be seen however that such opening does not result in a material waste of water because immediately thereafter the supplemental valve begins automatically to close, but at such a predetermined rate as will prevent any undue increase of pressure until finally a complete closure is effected.

It will thus be seen that the only water used other than that required for actually driving the impact wheel is the small amount which is discharged from the compensating device when the load fluctuations are of such magnitude as would tend to cause disturbance in the pipe line if not compensated for, so that there is a most material economy effected in the use of the motor fluid.

The compensating nozzle does not come into operation at all during the normal movements of the main valve mechanism, but operates only in case of a sudden increase of speed and then only when the main valve mechanism is moved to a predetermined closed position. The connection to the compensating nozzle is a direct connection as distinguished from a connection through a motor as in my co-pending application Serial No. 303,219.

I do not here claim the combination with the main port and its valve, of compensating means consisting of a supplemental port and valve, as this is the subject of a separate application for Letters Patent No. 205,606.

Without limiting myself to the precise construction and arrangement of parts shown, I claim as my invention:

1. A valve casing having main and supplemental ports and valves, a device connected to shift both valves, and a direct connection with the supplemental valve including a fluid medium capable of yielding to a limited extent under the movement of one part of the connection and constructed and arranged to permit a partial sudden closing or a slow and complete closing of the main port without opening the supplemental port.

2. In combination, a valve casing having main and supplemental ports and valves, a device connected to shift both valves, the connection with the supplemental valve being direct and including a dash-pot constructed to permit the closing of the main valve by a slow movement without opening the supplemental valve, said supplemental valve being closed by means independent of the dash-pot, and the connections to the two valves being structurally independent of each other.

3. The combination with the valve casing and main and supplemental ports and valves, of a device connected to the main

valve and directly connected to the supplemental valve to shift both valves, means in the line of connection between said device and the supplemental valve constructed and arranged to insure the simultaneous sudden movement of both valves in reverse directions while permitting a slow closing movement or a partial sudden movement of the main valve without shifting the supplemental valve.

4. The combination of the casing having main and supplemental ports and valves, means for operating said valves, a dashpot in the connection between the supplemental valve and said means, the said dashpot having a piston and ports arranged to permit a free movement of one part of the dashpot in respect to the other on the first part of the closing action of the main valve and restricting said movement as the main valve terminates its closing action.

5. The combination with the casing and main and supplemental valves and ports, of means for shifting said valves mechanically and connections between said means and supplemental valve consisting of a dashpot having a cylinder, piston and supply chamber, and with ports arranged to permit a preliminary free movement of one part in respect to another, and thereafter retard said movement.

6. The combination with the casing, its main and supplemental ports and valves attached thereto, and mechanical shifting means, of a piston and cylinder in the line of connection between the shifting means and the supplemental valve, the said cylinder having ports arranged to permit the free outflow of the liquid from the cylinder during a part of the closing movement of the main valve, and a second port arranged to allow a restricted outflow of the liquid during the remaining portion of said movement.

7. The combination with the supplemental valve having a head adapted to receive water pressure to close the valve, and a mechanical shifting means, of an intervening piston and cylinder, the latter having a port 21 affording a free flow of the liquid from the cylinder during the first part of the movement of the shifting means, and arranged to be then closed by the piston, and a second port 22 of restricted area, for the purpose set forth.

8. The combination with the supplemental valve D, mechanical shifting means and intervening connections including a piston and cylinder, of a casing communicating with the cylinder through ports 20, 21 and 22, port 21 being provided with a detachable perforated bushing, for the purpose described.

9. The combination with the supplemental valve D, mechanical shifting means and

intervening connections including a piston and cylinder, of a casing communicating with the cylinder through ports 20, 21 and 22, port 22 provided with adjustable means 5 for varying the flow therefrom.

10. The combination, with the supplemental valve and shifting means, of connections including a dash pot with ports arranged to permit a preliminary free movement of one 10 part of the dash pot with respect to the other as the shifting means move to open the valve, and to thereafter restrict the flow of the liquid to carry both parts of the dashpot with the shifting means.

15. 11. The combination with the casing and valve therefor, supplemental port and valve therefor having a head arranged to load the valve under water pressure, of means for shifting both valves mechanically, and connections between said means and the valves, one of said connections, including a dashpot, the latter having ports arranged to permit one part of the dash pot to move in respect to the other under the closing action 25 of the valve under pressure, and to insure the travel of both parts of the dashpot on moving the shifting means to open the valve.

12. The combination with a casing having main and supplemental ports and valves, a 30 supplemental valve having a head whereby it is loaded under water pressure, of shifting means for the main valve and connections between the same and the supplemental valve including a dashpot and piston, the 35 dashpot and piston having ports arranged to permit the valve to close independently of the shifting means under pressure upon the head of the valve, and to insure the travel of the dashpot with the shifting 40 means when the latter is moved to open the valve.

13. The combination of a casing having main and supplemental ports and valves, and mechanical means for shifting the 45 valves, the supplemental valve having a head receiving water pressure to close the valve, of connections between the shifting means and the supplemental valve, including a dashpot and piston with ports arranged to permit one part of the dashpot to be shifted freely on moving the shifting means to close the main valve, and to restrict the flow of liquid from the dash pot toward the final portion of the closing movement of the main valve, for the purpose set forth.

14. The combination with a hydraulic motor provided with valve mechanism, of a compensating device having a discharge 60 port and valve, a speed governor connected to said valve mechanism; a yielding direct connection between said governor and compensating device constructed to come into operation to operate the compensating device only when said valve mechanism is

shifted beyond a predetermined speed, and means separate from said connection for restoring said device after it has been operated.

15. The combination with a hydraulic motor provided with valve mechanism, of a compensating device having a discharge port and valve, a speed governor connected to said valve mechanism, and a yielding direct connection between said governor and compensating device constructed to come into operation to operate the compensating device only when said valve mechanism is shifted beyond a predetermined speed and limit in closing. 70

16. The combination with a hydraulic motor provided with valve mechanism of a compensating device having a discharge port and valve, a speed governor connected to said valve mechanism, a direct connection between said governor and compensating device including a dash-pot constructed to come into operation to operate the compensating device only when said valve mechanism is shifted beyond normal limits, and means separate from said dash-pot for restoring said device after it has been operated. 85

17. In a hydraulic motor, the combination with main and compensating nozzles and valves therefor, of a direct connection between said valves including a dash-pot, and hydraulic means separate from said dash-pot for closing said compensating valve. 95

18. In a hydraulic motor, the combination with main and compensating nozzles and valves therefor, of a direct connection between said valves including a cataract device, and a head on the compensating valve acted upon by the water to close the same. 105

19. In a hydraulic motor, the combination with main and compensating nozzles and valves therefor, of a governor for shifting the main valve, a dash-pot directly connected to said compensating valve and to said governor, and means separate from said dash-pot for closing said compensating valve. 110

20. In a hydraulic motor, the combination with main and compensating nozzles and valves therefor, of a governor for shifting the main valve, a cataract device directly connected to said compensating valve and to said governor, and a head on said compensating valve acted upon by the water to close the same. 120

21. In a hydraulic motor, the combination with main and compensating nozzles and valves therefor, of a governor for shifting the main valve, and a dash-pot directly connected to said compensating valve and to said governor, and constructed to come into operation only when the main valve 125

is shifted beyond a predetermined closed position.

22. The combination with a hydraulic motor provided with valve mechanism, of 5 a compensating device having a discharge port and valve, a speed governor, and a direct connection between governor and compensating device, constructed and arranged to cause the said compensating valve 10 to be shifted to open its port only when the motor valve moves beyond a predetermined speed and limit in closing.

23. In a hydraulic motor, the combination with main and compensating nozzles 15 and valves therefor, of a governor for shifting the main valve and having a connection with said compensating valve, a yielding device in said connection, and a head on said compensating valve constructed to 20 cause the water pressure to close said valve against the yielding device.

24. The combination with a hydraulic motor, of a water supply pipe, a bifurcated nozzle rigidly secured thereto, a device 25 working in one branch of the nozzle for varying the outlet area thereof to regulate the quantity of an impact stream discharged therefrom, means for causing the movement of said device, an overflow outlet in the 30 opposing branch of the nozzle, a valve for controlling the said overflow outlet, means actuated by the device for varying the outlet area for the impact stream adapted to cause the opening of the overflow outlet

after the partial closing of the outlet for 35 the said impact stream, said means and said valve being constructed and arranged to permit the gradual closing of the same.

25. The combination with a hydraulic motor provided with valve mechanism, of 40 a compensating device having a discharge port and valve, and means connecting said valves including a yielding member adapted to be operated from a speed governor constructed and arranged to cause the valve 45 of the said device to be shifted to open its port only on an undue increase of speed of the apparatus and if the valve mechanism suddenly approaches its closed position. 50

26. The combination with the valve casting and main and supplemental ports and valves, of a device connected to shift both valves, means in the line of connection between said device and the supplemental 55 valve constructed and arranged to insure the simultaneous sudden movement of both valves in reverse directions while permitting a slow closing movement or a partial sudden movement of the main valve without shifting the supplemental valve. 60

In testimony whereof I affix my signature in presence of two witnesses.
